J. J. LYCETTE ET AL

APPARATUS FOR AND METHOD OF SOFTENING THE EARS OF BOX TOE STIFFENERS

Filed Sept. 2, 1921

UNITED STATES PATENT OFFICE.

JOHN J. LYCETTE AND ERNEST NADREAU, OF NASHUA, NEW HAMPSHIRE.

APPARATUS FOR AND METHOD OF SOFTENING THE EARS OF BOX-TOE STIFFENERS.

Application filed September 2, 1921. Serial No. 497,868.

To all whom it may concern:

Be it known that we, JOHN J. LYCETTE and ERNEST NADREAU, citizens of the United States, residing at Nashua, in the county of Hillsborough and State of New Hampshire, have invented certain new and useful Improvements in Apparatus for and Methods of Softening the Ears of Box-Toe Stiffeners, of which the following is a specification.

10 This invention relates to an apparatus for use in the manufacture of boots and shoes, and its particular purpose is for use in softening the ears of the box toe stiffener after the shoe upper and inner sole have been assembled on the last, and after substantially the whole of the box toe stiffener has been softened by means of moisture or steam and has been tacked to the last at the point of the shoe and at the wings of the toe-cap stiffener, but before the shoe has been lasted for the welt.

When the toe-cap stiffener has been thus tacked in position, ears are left sticking out on each side of the point and as they have 25 now hardened, it is necessary to again soften them in order to make a smooth, satisfactory toe for lasting.

We are well aware that there are many types of moisteners wherein water, steam 30 and vapor are used, but there are now a vast number of shoes made of what is known as painted leather, which is stained by steam or moisture.

Specifically our device is to apply vapor 35 or steam to the projecting ears only of the toe-cap stiffener and incidentally to the adjoining part of the lining and to a certain extent to the adjoining part of the toe-cap which will be concealed in the finished shoe 40 but without touching the leather forming the outside of the shoe.

Our invention includes a pocket for the front of the shoe, a moisture chamber or box for supplying moisture thereto, and a 45 rest, preferably of a special form, for holding the unfinished shoe in the right position in the pocket.

In the drawings, Fig. 1 is a side sectional elevation of our device with an assembled 50 shoe on the last in position.

Fig. 2 is a detail showing location of a pinhole.

Fig. 3 shows another location of a pinhole which may be used.

55 Fig. 4 is a plan view of a shoe at the stage

of the shoemaking process where our apparatus is useful.

Fig. 5 is a side sectional elevation showing a modification of our device.

Fig. 6 is a sectional elevation on line 6—6 60 of Fig. 1.

Fig. 7 is a perspective of another form of shoe rest.

Fig. 8 is a sectional elevation of a modified form of pocket. 65

In the drawings, A represents the moisture containing box supported in any suitable manner as by legs 8 and having a top 5, bottom 6, front 7, back 4, and sides 9, and 9 not shown. This box may, however, 70 be of almost any shape. It should be steam tight and should have no outlets except those to be described. E represents a steam inlet pipe from any suitable source of steam, preferably having an elbow at 20 and extending down at 21 into and proximate the bottom 6 of box A. Preferably this inlet pipe is provided with a valve 61 outside box A. 75

F represents a drip pipe which passes 80 down through the bottom 6 of box A, having its inlet 22 located above the lower end 21 of steam inlet pipe E and preferably having a control valve 52 by which the amount of water and steam passing out 85 through the bottom 23 of drip pipe F may be regulated if it becomes necessary.

The bottom of box A may be filled with water by condensation of steam from the pipe E, or may be filled otherwise to the 90 water level W, which will always remain even with the top 22 of the drip pipe.

Extending out from the front of box A are brackets 41, 41, carrying a suitable rest 40 to partly support an unfinished shoe consisting of a vamp V, inner sole I, lining C and toe-cap stiffener T. The vamp and lining are tacked on each side to the last by tacks 12, 12, and the wings 70 and 71 of the toe-cap and the wings of the toe-cap stiffener T which are under them, are tacked to the last on each side by tacks 11, 11, while the front of the toe-cap and toe-cap stiffener are tacked to the tip of the last by tacks 10 95

which force outward the ears 30 and 31 of the toe-cap stiffener. This rest 40 is so positioned that the weight of the last would 100

cause it to tip over backwards or to the right, as shown in Fig. 1, except for 105

Fig. 4 is a plan view of a shoe at the stage pocket B. 110

B represents a toe pocket which is steam proof and is located above rest 40 and extends in from the front of box A. It has an inwardly and downwardly sloping top wall 24, and through each of its side walls 59 near its upper inner side is a pinhole 26 which is the only outlet to permit the escape of vapor or steam from box A, except through the outlet F.

10 The front 57 of pocket B is open and large enough to admit the toe part of a shoe, while the inner wall 58 may be of any suitable shape.

15 As shown in Figs. 1 and 2, pinholes 26 will preferably extend through the side walls, but as shown in Fig. 3, a single pinhole 66 may be located in the back or inner wall 58.

20 Projecting down from top 24 of pocket B is a spacing pin 25 which is shown as a screw whereby the space through which the vapor can escape may be adjusted.

25 The unfinished shoe, upside down, with the last, is pushed into pocket B and rested on to 40. Its tendency to tip out causes the sole to remain in contact with pin 25, leaving a space between the sole and top 24 through which vapor from the pinhole or pinholes can pass.

30 The operation of the device is that steam, entering through pipe E at S¹, bubbles up at S² through the water, and continues as wet steam or vapor at S³ until it passes into pocket B through the holes 26 or a hole 66, and then, being lighter than air, it travels along under the sloping top wall 24 and out at S⁴. In its passage it softens the ears 30 and 31 of the toe-cap stiffener T without reaching that part of the vamp 35 which in 40 the finished shoe will be on the top of the toe.

35 As shown in Fig. 5, we may use a pocket H in box A which has a sloping top wall 24 and pinholes 26, but which has no spacing pin and which has its bottom wall 50 sloping down and out so that if any water should condense it would flow down and out and so that the air can circulate freely from outside up in the direction of the arrow, thereby helping to keep the part 35 of the toe at all times dry.

40 Instead of a steam pipe, a moisture pipe K with a valve 53 may be used, and through this a spray of water or water mixed with air may be forced instead of steam for the purpose of filling and keeping filled box A with moisture.

45 As shown by the dotted lines marked 49 in Fig. 1, if it becomes necessary with some classes of shoes, an asbestos pad can be placed on the bottom 56 of pocket B to protect the upper leather from heat therefrom.

50 Where the spacing pin is omitted, as shown in Fig. 5, the ears 30 and 31 them-

55 selves rest against the top of pocket and so 65 keep the space for the vapor to pass through between the inner sole I and the top 24.

The pocket may be integral with the box, as shown in Fig. 5, or it may conveniently be made with flanges 80 and 81 bolted to the 70 front of box A by means of bolts 82 and 83, as shown in Fig. 1.

75 The outlet F may drip on to the floor or into a pan, or may be connected with a return pipe to the steam boiler so that steam will be saved and the only steam which escapes will come through the pinholes such as 26.

80 As it is very necessary that the unfinished shoe should be placed in the right position 80 in the pocket in order that moisture may reach exactly the right parts and in order that the tip of the toe 35 should not become burned, we prefer to provide a substantially 85 automatic rest which will make it difficult, if not impossible, for an unskilled operator to place the shoe in the wrong position. We also prefer to so arrange this that there will be no part in contact with the shoe 90 vamp or upper which will become hot and thus stain it.

95 We prefer to accomplish this by attaching parallel brackets 41 and 41, preferably by means of the bolts 83, which connect the lower flange 81 with box A, such brackets 95 extending out and up to a point which will be behind the center of gravity of the shoe and last. There are series of holes 42, 42 passing through each bracket, and between any two of them, at a point nearer the box 100 A than the center of gravity, we connect the opposite ends of a coil spring 40 in such manner that it will hang down and form a loop, as shown in Fig. 6. This should be 105 adjusted in the right position and should be of the right strength so that when the operator is pushing the toe of the shoe into the pocket, a point on the instep will strike the looped rest and catch it so that if the toe is pushed too far in, when released by 110 hand, the swinging rest 40 will carry it out away from the back 48 of the pocket. The loop of the rest 40 being made of coil wire, which permits the free circulation of air, 115 will not become hot.

As shown in Fig. 7, however, instead of a spring, we may use a band 84 of cloth, tape or rope made of any material which is a non-conductor and which will remain cool.

120 As shown at 85 in Fig. 5, the bottom wall 50 of the pocket may be practically eliminated. This might so distort the pocket that the apparatus would have more of the nature of an inwardly projecting shelf, with a bottom wall 24 instead of a pocket with 125 a top wall 24, the principal necessary feature being that the passages for the moisture should be proximate the lower end of

the top wall close to which, but preferably out of contact with which the sole of the shoe is held.

We claim:

5. 1. In an apparatus for softening the ears of box toe stiffeners, the combination with a moisture containing box, of a steam inlet which extends down into and proximate the bottom thereof, a drip pipe through said 10 bottom having its inlet above the end of the steam inlet, a shoe rest outside the box adapted to partly support an unfinished shoe and last, and a toe pocket located above the said rest and extending into said box having an inwardly and downwardly sloping top wall and a pinhole in each of its upper inner side walls to permit the only escape of vapor from said box except through said outlet, together with an adjustable spacing 15 pin which projects down from the top of said pocket.

2. In an apparatus for softening the ears of box toe stiffeners, the combination with a moisture containing box, of means for filling said box with moisture, a shoe rest outside the box adapted to partly support an unfinished shoe and last, and a pocket located above said rest and extending into said box having an inwardly and downward- 20 ly sloping top wall and a passage proximate its upper inner portion from inside of the box to permit the only escape of vapor therefrom except through said outlet, together with a spacing pin which projects down 25 from the top of said pocket.

3. In an apparatus for softening the ears of box toe stiffeners, the combination with a moisture containing box, of means for filling said box with moisture, a shoe rest outside the box adapted to partly support an unfinished shoe and last upside down, and a pocket located above said rest and extending into said box having an inwardly and downwardly sloping top wall and a passage proximate its upper inner portion from inside of the box to permit the only escape of vapor into said pocket.

4. In an apparatus for softening the ears of box toe stiffeners, the combination with a moisture containing box, of a steam inlet which extends down into and proximate the bottom thereof, a drip pipe through said bottom having its inlet above the end of the steam inlet, a shoe rest including a looped coil spring hung between two brackets outside the box adapted to partly support an unfinished shoe and last, and a toe pocket located above the said rest and extending into said box having an inwardly and down-

wardly sloping top wall and a pinhole in 60 each of its upper inner side walls to permit the only escape of vapor from said box except through said outlet, together with an adjustable spacing pin which projects down from the top of said pocket.

5. In an apparatus for softening the ears of box toe stiffeners, the combination with a moisture containing box, of means for filling said box with moisture, a shoe rest including a looped coil spring hung between two brackets outside the box adapted to partly support an unfinished shoe and last, and a pocket located above said rest and extending into said box having an inwardly and downwardly sloping top wall 70 and a passage proximate its upper inner portion from inside of the box to permit the only escape of vapor therefrom except through said outlet, together with a spacing pin which projects down from the top 75 of said pocket.

6. In an apparatus for softening the ears of box toe stiffeners, the combination with a moisture containing box, of means for filling said box with moisture, a shoe rest 85 including a loop hung between two brackets outside the box adapted to partly support an unfinished shoe and last, and a pocket located above said rest and extending into said box having a sloping top wall and a 90 passage proximate its lower end from inside of the box to permit the only escape of vapor therefrom except through said outlet, together with a spacing pin which projects down from the top of said pocket.

7. In an apparatus for softening the ears of box toe stiffeners, the combination with a moisture containing box, of means for filling said box with moisture, a shoe rest including a loop hung between two brackets 100 outside the box adapted to partly support an unfinished shoe and last upside down, and a pocket located above said rest and extending into said box having a top wall sloping sharply upward and a passage proximate 105 its lower end from inside of the box to permit the only escape of vapor therefrom into said pocket.

8. The process of softening the ears of box toe stiffeners after the box toe has been 110 tacked to the last which consists of bringing the ears with the last upside down and the heel above the toe up against the under side of a flat surface which slopes sharply upward and introducing steam or water vapor 115 in small quantities proximate said ears.

JOHN J. LYCETTE.
ERNEST NADREAU.
